GEORGE F. MERKLEE, OF NEW YORK, N. Y.

Letters Patent No. 72,520, dated December 24, 1867.

IMPROVEMENTS IN HOT-AIR FURNACES.

The Schedule referred to in these Letters Patent and making part of the same.

Specification of Improvements in Air-Heating Furnaces for Warming Dwellings, &c., invented by GEORGE F. MERKLEE, of the city, county, and State of New York.

My improvements are made in the construction of the parts of an air-heating furnace above the fire-pot, therefore the fire-pot and parts below it need no specific description.

My invention consists, first, in the peculiar form of the plate which rests upon the top rim of the fire-pot, and the tubes or air-passages arranged upon it, in combination with the annular smoke-flue extending upward beyond said air-passages, for the purpose of providing a large amount of heating-surface, and obliging the products of combustion to pass over the whole of said surface in their course to the exit-pipe; second, in the combination with annular flue, air-passages, and dome, of a cylinder extending downwards to a point about half the height, and within the line of the air-passages, for the purpose of preventing the hot products of combustion, which rise into the dome above the fire-pot, passing too freely outward into the annular smoke-flue, and, also, for the purpose of equalizing the action of the smoke and gases upon the fire-surface of the air-passages, by holding them for a longer time against said surface, while, at the same time, the cylinder does not obstruct the reflection of the fire upon the said air-passages or tubes; third, the combination, with the annular flue, of a cross-pipe and central exit-pipe, whereby the products of combustion, which pass outward from the fire-pot, are returned to the centre of the furnace before they can pass into the exit-pipe, and thence into the chimney. In the accompanying drawings, in which like letters refer to like parts—

Figure 1 is a front elevation of the furnace, with outside cylinder or casings attached.

Figure 2 is a vertical central section of the furnace, taken from front to rear.

Figure 3 is a horizontal plan of the furnace, taken at the line W in fig. 2.

Figure 4 is a horizontal plan of the furnace, taken at the line V in fig. 2.

G is a plate resting upon and forming a joint with the top rim of the fire-pot F, which plate extends upward and outward to a line within the inner circle of the air-tubes or passages I I I I I, and thence outward horizontally beyond the outer circle of said air-passages to the cylinder M, with which it forms a joint. In the horizontal portion of the plate G is a series of openings extending through it, to admit the air to be heated to the air-passages I.

These tubes or air-passages extend upward from the plate G, through the combustion-chamber, outside of the cylinder J, to the flat plate K, with which they form a joint. Extending upward from the outer line of the plates G and K are the cylinders L and M, which form the annular flue b, which is closed at the top by the flat plate S. Extending upward from the inner line of the flat plate K is the cylinder O O, which is closed at the top by plate P, forming the dome e. Extending across the air-chamber d, from the cylinder L, is the cross-pipe Q, which connects the annular smoke-flue b with the exit-pipe R. Surrounding and enclosing the whole is the cylinder N, and top of same, U, which forms the air-chamber f, into which the air to be heated is conveyed through the opening D, in the base A, and passing over the surfaces of the plates G, K, S, and P, cylinders O, L, M, and through the air-passages I, passes through the openings T to the tin pipes, thence to the different apartments which are to be warmed.

My invention consists in giving to the plate G the form shown in drawings, figs. 2 and 3, for the purpose of remedying defects which have heretofore existed. In furnaces where tubular plates are used, it has been common, prior to my invention, to make them flat, and it has also been claimed as new to make these plates to incline inward and downward from the cylinder M to the fire-pot F. In the flat plate, radiating surface is lost to a very great extent, as it is not exposed to the direct action of the fire, and accumulates upon it non-conducting substances. In the inclined plate, where the inclination is great, the accumulation of non-conducting matter upon it will be prevented, but a very serious objection to this form of plate is the casting on it of necks or collars to receive the air-passages I. The joints between the necks and air-passages being very near, and exposed to the direct action of the fire, become very much expanded, and, as a natural consequence, bulge out open, and leak gaseous matter into the air-passages—a very serious defect.

In my form of plate, the inclination being from the inner line of the air-passages I, presents to the direct action of the fire the required radiating-surface, without the accumulation upon it of any non-conducting substances. This inclined part of plate G may be plain or corrugated, as shown in figs. 2 and 3.

That portion of the plate S upon which the air-passages I are arranged is made perfectly flat, so that ashes may accumulate upon it, and thereby make the joints between the plate G and air-passages I self-packing and perfectly tight. In order to make the inclined surface of the plate G a more effectual heating-surface, I have arranged the annular flue b. By this means I oblige all the products of combustion to pass outward over the inclined surface, and around the air-passages, in their course to the exit-pipe. Thus my invention affords a large amount of perfect heating-surface, and horizontal joints for the air-passages, without the great inconvenience of casting necks or collars upon any part of the tubular plate.

Another very important feature in my invention is extending the cylinder J J downward from the plate K, by which arrangement I hold against the surface of the dome e the hot products of combustion, and oblige them, when cooled by radiation into the air-chamber d, to pass down below the mouth of the annular flue b, and mingle again with the hot currents arising from the fire, without obstructing the reflection of the fire upon the air-passages I.

Another feature of my invention is the cross-pipe or horizontal smoke-flue Q, through which the hot products of combustion pass inward to the exit-pipe R, in the centre of the furnace, for the purpose of increasing the heating-surface within the air-chamber d.

Having thus described my invention, what I claim is—

1. The combination, in an air-heating furnace, of the plate G, constructed substantially as described, with the air-passages I I I I and annular flue b, for the purpose as set forth.
2. The combination, in an air-heating furnace, of the dome e, air-passages I I I I, and annular flue b, with the cylinder J J, or its equivalent, substantially as for the purpose set forth.

GEORGE F. MERKLEE.
